(57) **CLAIM**

The ornamental design for a safe, as shown and described.

DESCRIPTION

FIG. 1 is a perspective view of a safe according to a first embodiment of the present design.

FIG. 2 is a front elevation view of the safe of FIG. 1 with a door, door hinges, a combination entry portion, a handle assembly, and a top shelf shown in phantom.

FIG. 3 is a rear elevation view of the safe of FIG. 1 with the top shelf shown in phantom.

FIG. 4 is a right side elevation view of the safe of FIG. 1 with the door hinges, the handle assembly, and the top shelf shown in phantom.

FIG. 5 is a left side elevation view of the safe of FIG. 1 with the door hinges, the combination entry portion, the handle assembly, and the top shelf shown in phantom.

FIG. 6 is a top plan view of the safe of FIG. 1 with the top shelf, the handle assembly, the door hinges, and the combination entry portion shown in phantom.

FIG. 7 is a bottom plan view of the safe of FIG. 1 with the handle assembly, the door hinges, and the combination entry portion shown in phantom.

FIG. 8 is a perspective view of a safe according to a second embodiment of the present design.

FIG. 9 is a front elevation view of the safe of FIG. 8 with a door, door hinges, a combination entry portion, a handle assembly, and a support for a top shelf shown in phantom.

FIG. 10 is a rear elevation view of the safe of FIG. 8 with the support for the top shelf shown in phantom.

FIG. 11 is a right side elevation view of the safe of FIG. 8 with the door hinges, the handle assembly, and the support for the top shelf shown in phantom.

FIG. 12 is a left side elevation view of the safe of FIG. 8 with the door hinges, the combination entry portion, the handle assembly, and the support for the top shelf shown in phantom.

FIG. 13 is a top plan view of the safe of FIG. 8 with the top shelf, the handle assembly, the door hinges, and the combination entry portion shown in phantom; and,

FIG. 14 is a bottom plan view of the safe of FIG. 8 with the handle assembly, the door hinges, and the combination entry portion shown in phantom.

The broken lines illustrate portions of the safe which form no part of the claimed design.
